UNITED STATES PATENT OFFICE.

THOMAS BRUNSON STEPHENSON, OF BRISTOL, CONNECTICUT.

DESIGN FOR A BADGE.

SPECIFICATION forming part of Design No. 27,929, dated December 7, 1897.

Application filed August 28, 1897. Serial No. 649,887. Term of patent 3½ years.

To all whom it may concern:

Be it known that I, THOMAS BRUNSON STEPHENSON, of the town of Bristol, in the county of Hartford and State of Connecticut, have 5 invented and produced a new and original Design for a Badge, of which the following is a specification, reference being had to the accompanying drawing, forming a part thereof.

The drawing represents my design in perspective.

The leading feature of my design is the combination for a scarf-pin, badge, or emblem of the jackass and three links.

A represents the jackass.

15 B B are the three links.

The jackass is shown mounted upon the links, the fore feet resting upon one of the outside links and the hind feet upon the other outside link.

Having thus described my invention, what 20 I claim is—

A design for a badge substantially as herein shown and described.

In testimony whereof I have signed this specification in the presence of two subscribers. 25

THOMAS BRUNSON STEPHENSON.
